DESIGN FOR A BOOK END

George P. Hendricks, Oakland, Calif., assignor of one-half to John Cruze, Hayward, Calif.

Application March 14, 1939, Serial No. 83,572

Term of patent 14 years

To all whom it may concern:

Be it known that I, George P. Hendricks, a citizen of the United States, residing at Oakland, in the county of Alameda and State of California, have invented a new, original, and ornamental Design for a Book End, of which the following is a specification, reference being had to the accompanying drawing, forming a part thereof.

I claim:

The ornamental design for a book end, substantially as shown.

GEORGE P. HENDRICKS.
